UNITED STATES PATENT OFFICE

ALBERT A. GORDON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

TWO-WEAVE DOBBY

Application filed January 16, 1928. Serial No. 246,953.

This invention relates to improvements in dobbies capable of producing two different weaves and it is the general object of the invention to provide a dobby having an auxiliary pattern cylinder and a set of indicating fingers therefor the pivots of which are movable so that different portions of the fingers may be opposite the pattern cylinder at different times.

10 The invention set forth herein is more particularly related to the form of so-called name dobby set forth in my prior Patent No. 1,060,977. A dobby of this type may be used for the weaving of names or other identification marks in the selvages of cloth, and is usually mounted on the arches of the loom to act in addition to the ordinary shedding mechanism to control only a few of the warp threads. The devices set forth herein, however, need not necessarily be limited to a name dobby, but may be used to control larger groups of warp threads.

15 The dobby shown in said patent has been provided with an auxiliary upper cylinder as set forth in my co-pending application Serial No. 203,417, the cylinder moving about a fixed axis and the pattern mechanism being necessarily provided with a blank space to be presented opposite the controlled fingers 20 when the auxiliary cylinder is idle and the main cylinder is in operation. In another later filed co-pending application Serial No. 237,071 I have shown means for raising the auxiliary cylinder so that it is not necessary to provide the pattern surface with a blank space. The forms of mechanism shown in said applications have worked successfully but the necessity for raising the auxiliary cylinder introduces certain objections which are intended to be corrected by the invention set forth herein. It is an important object of my present invention to keep the axis of the auxiliary cylinders substantially fixed and to provide a set of fingers 25 having surfaces of two different heights, the higher surface being positioned to cooperate with the pattern surface when the fingers are in one position and the low surface being opposite but out of the range of 30 the pattern surface when the fingers are in

another position. The fingers for the auxiliary cylinder are pivoted about a rod or shaft which is movable under control of the main pattern mechanism. The axis of the auxiliary pattern surface may be substantially stationary but the pattern surface need not be provided with a blank space, inasmuch as the low portions of the indicator levers accomplish the same result as the blank space in the first of the aforesaid applications.

35 It is a further object of my present invention to provide a pair of alternately operative pattern surfaces made up of bars which present a continuous pattern without blank spaces, said cylinders moving about fixed axes and one of the cylinders cooperating with levers moving about a fixed center while the other pattern surface cooperates with the levers pivoting about a movable center.

40 With these and other objects in view which will appear as the description proceeds, my invention resides in the combination and arrangement of parts hereinafter described and set forth in the claims.

45 In the accompanying drawings wherein one form of my invention is shown,

Fig. 1 is a side elevation of a dobby mechanism having my invention applied thereto, the parts being in a position to permit control of the warp by the upper or auxiliary cylinder,

50 Fig. 2 is a top plan taken in the direction of arrow 2, Fig. 1 showing the left hand portion of the dobby,

Fig. 3 is a detail front elevation taken in the direction of arrow 3, Fig. 1,

55 Fig. 4 is a detail vertical section on line 4-4 of Fig. 3 showing the lower end of the pawl for the upper cylinder, and

Fig. 5 is a perspective view of one of the 60 indicating fingers for the top cylinder.

65 Referring to the drawings I have shown a loom arch 10 on which is mounted the dobby forming the subject matter of the present invention. Said dobby is provided with a pair of side plates 11 in which is mounted for periodic angular rotation a main pattern cylinder 12 having a pattern chain 13. A ratchet wheel 14 is secured to the shaft 15 on which the cylinder 12 is mounted so that said ratchet

wheel and cylinder move together. An actuating pull pawl 16 cooperates with the ratchet wheel 14 to give the cylinder periodic angular movements to bring the bars 13 of the main pattern chain under the dobby fingers

5 17 one at a time. The fingers are pivoted on a rod 18 which extends between the dobby plates 11 and certain of said fingers have upwardly extending tails 18^a while others have horizontally and rearwardly extending tails 19. Upright wires 20 and 21 cooperate, respectively, with the tails 18^a and 19 and said wires may be suitably guided as by racks 22 and 23, respectively, supported by the dobby plates 11. The upper ends of the wires 21 are bent back on themselves as at 24 and extend downwardly through the upper comb 22 while the upper ends of the wires 20 extend through said comb and project thereabove a slight distance.

20 Each harness jack 25 is pivoted to a lever 26 mounted pivotally on a pin 27 held by the plates of the dobby. A fixed pin 28 engages forward extension 29 of the jacks to cause upward movement of the latter when the levers 26 move in a clockwise direction around pin 27. In order to produce this movement of the levers 26 each of the latter has connected thereto as at 30 a dobby back lever 31 extending on both sides of the pivot 30. Each back lever has connected thereto an upper hook 32 and a lower hook 33. Said hooks cooperate with knives not shown herein but set forth in my aforesaid application Serial 25 No. 203,417. The hooks are raised and lowered whenever the corresponding fingers or indicating levers 17 are lowered or raised, respectively, in the manner set forth in my co-pending application Serial No. 237,071.

30 A multiplying unit M consisting of two chains 34 and 35 of different lengths may be employed if desired, each chain having a plurality of high links 36 and one of the low links indicated at 37 in Fig. 1. The multiplying unit need not necessarily be employed but is shown herein to indicate a means for keeping the upper cylinder to be described hereinafter idle for a large number of picks without an excessive length of chain on the main cylinder 13.

35 A rocker shaft 38 is given periodic oscillations by mechanism not shown, moving to the right on one pick and to the left on the next pick, etc. Secured to said shaft is an arm 39 to which the pawl 16 is pivotally connected as at 40. Another pawl 41 is also connected to said arm 39 and cooperates with the ratchet 42 which moves with the chains 34 and 35 causing the latter to have a step by step movement. A lever 43 is pivoted on the rod 18 and has a shoe 44 to cooperate with the links of the chains 34 and 35. A spring 45 connected to the lever 43 and one dobby plate tends to hold said shoe against the chains. An upwardly extending arm 46 has adjustably held

therein a pin 47 which cooperates with the pawl 16 and holds the latter in the inoperative position shown in Fig. 1 when a high link 36 on either of the chains 34 or 35 lies under the shoe 44.

40 Upstanding horns 49 support an upper cylinder 50 having a series of pattern chain bars 51 mounted thereon which provide the auxiliary pattern surface referred to herein. A ratchet wheel 52 is secured to the shaft 53 on which the cylinder 50 is secured and the upwardly extending pawl 54 cooperates with said ratchet 52 when the main pattern surface is idle. The control for the pawl 54 includes a depending arm 55 preferably cast integral with the pawl 54 and movable loosely around the stud 40. The lower end of said arm 55 is provided with a cam face 56 which terminates in a relatively low face 57 on the upper side thereof and in a relatively high surface 58 on the lower side thereof. An extension 59 formed as part of a lever 60 pivoted on rod 18 cooperates with the lower end of arm 55 to control pawl 54. As shown in Fig. 4 when the lever 60 is in the position shown in Fig. 1 the extension 59 will be up and opposite the relatively low surface 57 so that spring 60^a interposed between the pawl 54 and one of the dobby plates will hold said pawl in operative position with respect to the ratchet wheel 52. A finger 48 carried by the lever 60 engages the right hand side of the lower end of pawl 41 as shown in Fig. 1 and acts to hold said pawl out of engagement with the ratchet wheel 42 when the right hand end of lever 60 is down.

45 Under normal conditions, with the main cylinder operative, two low links 37 will be under shoe 44 and pawl 16 will engage ratchet 14 to give cylinder 12 a step by step movement. The foot 61 on the right end of the lever 60 as viewed in Fig. 1 will be down and finger 48 will hold pawl 41 inoperative and extension 59 will be opposite the high surface 58 at the time pawl 54 has a down motion, so that the said pawl 54 will miss the ratchet 52. As the main cylinder continues to rotate a peg 62 will eventually arrive under foot 61 to lift the lever 60 to the position shown in Fig. 1. Finger 48 will thereupon move to the right to permit pawl 41 to turn the multiplier chains and extension 59 will rise to a position opposite the low surface 57 to permit pawl 54 to become operatively related to the auxiliary cylinder. On the next down stroke of pawl 41 high links 36 will move under shoe 44 to cause pin 47 to render pawl 16 inoperative with respect to the main cylinder. The upper cylinder will remain active until the low links 37 again arrive under shoe 44, at which time the pawl 16 will move peg 62 away from foot 61 and lever 60 will have a right hand oscillation to cause cessation of movement of the multiplying unit and the auxiliary cylinder. A spring 8 interposed between lever 43 and

finger 48 tends to hold the parts in the position shown in Fig. 1. The matter thus far described is set forth to show how my invention described hereinafter may be utilized but forms no part of my present invention and may be substantially the same as so-called name dobbies now in use.

In carrying my improvements into effect I provide improved and simplified means for communicating indications from the upper or auxiliary pattern chain to the hooks 32 and 33. The rear end of said lever 60 is slotted as at 63 to receive a stud 64 having pivotal connection with the lower end of link 65. The slot affords adjustment of the stud so that the movement imparted to the link may be varied. The upper end of said link is pivoted as at 66 to one arm of the lever 67 pivoted on a stud 68 which is fast with respect to one of the plates of the dobby. The upper end of said lever 67 has secured thereto a rod 69 which extends across the dobby as shown in Fig. 2 and has pivoted thereto a series of depressor levers 70. There will be one lever 70 for each of the wires 20 and 21 and said levers will rest on the upper ends of the wires as indicated in Fig. 1, being light enough to be overbalanced by the fingers 17.

An important part of my present invention relates to the control of said depressor levers and as shown more particularly in Fig. 5 each of said levers is provided with a relatively high chain engaging surface 71 and a low surface 72 which will ordinarily be out of reach of the dobby pegs 73 carried by the links 51 when the parts are in such a position as to render the upper cylinder inactive.

In the operation of the device it may be assumed that the parts are in the position shown in Fig. 1 with the lower cylinder inactive and the upper cylinder receiving a periodic angular movement to bring a new bar 51 immediately over the depressor lever 70 at periodic intervals of the loom, such for instance as every second pick when the dobby is made as a so-called double index dobby as set forth herein. The relatively high surfaces 71 of the depressor levers will be in position to be engaged by the dobby pegs 73 and certain of the levers 70 will be depressed according to the demands of the pattern to lower the corresponding wires 20 and 21. This will effect control of the hooks 32 and 33 so that the harness jacks or levers 25 may receive movements corresponding to the demands of the pattern. When the parts are in the position shown in Fig. 1 the peg 62 will be under the foot 61 of the lever 60 and will remain in this position for as many picks as the upper cylinder is to be active. The period of action on the part of the auxiliary cylinder will be determined by the length of the chains 34 and 35 and when two low links 37 appear under the shoe 44 the pawl 16 will act to move the peg 62 from under

the foot 61, as previously described, at which time spring 80 interposed between one of the dobby plates and the lever 67 will move the latter to the left to the dotted line position indicated in Fig. 1. In this position the low areas 72 of the levers 70 will be under the auxiliary pattern surface and the wires 20 and 21 will therefore not be controlled by the auxiliary pattern. The chain on the main cylinder will be so pegged as to lift the foot 61 whenever it is desired to throw the depressor levers into operative position.

From the foregoing it will be seen that I have provided a two weave dobby for pattern mechanism wherein two cylinders each bearing an independent pattern chain are alternately rendered operative, each cylinder moving about a fixed axis and that the main cylinder cooperates with dobby fingers of the usual form which swing about a fixed center while the auxiliary cylinder cooperates with a set of depressor levers which swing around a movable pivot the location of which is determined by the main pattern chain. It will further be seen that the depressor levers are provided with high and low areas and that when the low areas are opposite the auxiliary pattern surface the latter will have no effect on the hooks of the dobby. It will also be seen that because of the formation of the depressor levers 70 it will not be necessary to leave a blank space on one of the bars of the auxiliary pattern chain but that said pattern may be continuous without blank spaces.

Having thus described my invention it will be seen that changes and modifications may be made therein by those skilled in the art without departing from the spirit and scope of the invention and I do not wish to be limited to the details herein disclosed, but what I claim is:

1. In a dobby having a main pattern surface and an auxiliary pattern surface each movable about a fixed axis and having dobby fingers to be controlled directly by the main pattern surface, a set of auxiliary fingers for the auxiliary pattern surface, means defining a pivot for said auxiliary fingers, intermediate elements between the auxiliary fingers and the dobby fingers whereby movement of an auxiliary finger will cause movement of the corresponding dobby finger, and means to move the pivot for said auxiliary fingers relatively to the axis of the auxiliary pattern surface to move said auxiliary fingers into and out of operative position with respect to the auxiliary pattern surface.

2. In a dobby having a main pattern surface and an auxiliary pattern surface each movable about a fixed axis and having dobby fingers to be controlled directly by the main pattern surface, a set of auxiliary fingers for the auxiliary pattern surface, means defining a pivot for said auxiliary fingers, intermediate elements between the auxiliary fingers

and the dobby fingers whereby movement of an auxiliary finger will cause movement of the corresponding dobby finger, and means to move the pivot for said auxiliary fingers relatively to the axis of the auxiliary pattern surface to move said auxiliary fingers into and out of operative position with respect to the auxiliary pattern surface, said auxiliary fingers at all times being in engagement with the intermediate elements.

3. In a dobby having a main pattern surface and an auxiliary pattern surface each movable about a fixed axis and having dobby fingers to be controlled directly by the main pattern surface, a set of auxiliary fingers for the auxiliary pattern surface, means to move said auxiliary fingers into and out of operative position with respect to the auxiliary pattern surface, and intermediate operative connections established between the auxiliary fingers and the dobby fingers for all positions of the auxiliary fingers, the auxiliary fingers being ineffective to move the connections to actuate the dobby fingers when said auxiliary fingers are out of position relatively to the auxiliary pattern surface.

4. In a dobby having a main pattern surface and an auxiliary pattern surface each movable about a fixed axis and having dobby fingers to be controlled directly by the main pattern surface, a set of auxiliary fingers for the auxiliary pattern surface, a pivotal support for said fingers, means to move said pivotal support to cause said auxiliary fingers to move into and out of operative position with respect to the auxiliary pattern surface, and intermediate connections having contact with the auxiliary fingers in all positions of the latter to connect said auxiliary fingers operatively with the dobby fingers.

5. In a dobby having a main pattern surface and an auxiliary pattern surface each movable about a fixed axis and having dobby fingers to be controlled directly by the main pattern surface, a set of auxiliary fingers for the auxiliary pattern surface having relatively high and low surfaces, a pivotal support for said fingers, means to move said support so that either the high or the low portions of the auxiliary fingers will be adjacent to the auxiliary pattern surface, and intermediate connections between the auxiliary and dobby fingers to cause movement of the latter when the auxiliary fingers are moved by the auxiliary pattern surface and in operative contact with the relatively high surfaces of the auxiliary fingers.

6. In a dobby having a main pattern surface and an auxiliary pattern surface each movable about a fixed axis and having dobby fingers to be controlled directly by the main pattern surface, a set of auxiliary fingers for the auxiliary pattern surface, means defining a pivotal support for said auxiliary fingers, means to move said pivotal support

to carry the fingers bodily toward and from operative position with respect to the auxiliary pattern surface, and means establishing connection between the auxiliary and dobby fingers when the auxiliary fingers are operatively related with respect to the auxiliary pattern surface to cause movement of the dobby fingers when the corresponding auxiliary fingers are moved by the auxiliary pattern surface.

7. In a dobby having a main pattern surface and an auxiliary pattern surface each movable about a fixed axis and having dobby fingers to be controlled directly by the main pattern surface, a set of auxiliary fingers, intermediate connections between said auxiliary fingers and the dobby fingers, a movable pivotal support for the auxiliary fingers, said fingers being supported in part by the pivotal support and in part by the intermediate connections between said fingers in all positions of the auxiliary fingers, and means to move the pivotal support for the auxiliary fingers to move the latter into and out of operative position with respect to the auxiliary pattern surface, said intermediate connections causing movement of the dobby fingers when the auxiliary fingers are in operative position with respect to the auxiliary pattern surface and are moved by the latter.

8. In a dobby having a main pattern surface and an auxiliary pattern surface each movable about a fixed axis and having dobby fingers to be controlled directly by the main pattern surface, a set of auxiliary fingers, a movable pivotal support for said auxiliary fingers, intermediate connecting members between the auxiliary and dobby fingers, said auxiliary fingers being supported jointly by the pivotal support and the connecting members when said auxiliary fingers are operatively related to the auxiliary pattern surface, and means to move said pivotal support to move the auxiliary fingers into and out of operative position with respect to the auxiliary pattern surface.

9. In a dobby, an auxiliary finger, an auxiliary pattern surface, a movable pivot for the finger, dobby fingers, intermediate connecting members operatively related to dobby fingers, said auxiliary finger having an extended lower portion to be in contact with the corresponding connecting member for all positions of the pivotal support and said auxiliary finger having relatively high and low surfaces which are adapted to be operatively and inoperatively, respectively, related to the auxiliary pattern surface.

In testimony whereof I have hereunto affixed my signature.

ALBERT A. GORDON.
